UNITED STATES PATENT OFFICE.

JOHN GÉRARD, OF TRENTON, NEW JERSEY, ASSIGNOR TO THE TRENTON LOCK AND HARDWARE COMPANY, OF SAME PLACE.

DESIGN FOR PADLOCKS.

Specification forming part of Design No. **11,259**, dated June 24, 1879; application filed May 5, 1879.
[Term of patent 7 years.]

To all whom it may concern:

Be it known that I, JOHN GÉRARD, of Trenton, New Jersey, have produced or invented a new and original Design for a Padlock, of which the following is a specification.

My design for a padlock is fully shown in the accompanying drawings, in which Figure 1 is a front view, and Fig. 2 a rear view, of the lock.

The front plate of the lock has formed thereon representations of an eagle, *a*, and stars *b*, arranged on a striped background, *d*, as fully shown in Fig. 1.

On the rear plate of the lock is a representation of a shield, *e*, crossed by a scroll, *f*, on which is inscribed the word "Liberty." On the rear plate are also representations of stars *i*, the whole being arranged on a striped background, *m*.

The shackle has a narrow border on each edge, and is ornamented on each side by a row of stars, *n*.

I claim—

1. The design for the front plate of the lock, said design comprising the representation of the eagle *a* and stars *b*, arranged in respect to each other, all substantially as described and shown.

2. The design for the front plate of the lock,

said design comprising the representation of the eagle *a* and stars *b*, arranged in respect to each other on a striped background, *d*, all substantially as shown and described.

3. The design for the rear plate of the lock, said design comprising the representation of a shield, *e*, with scroll *f*, all substantially as described and shown.

4. The design for the rear plate of the lock, said design comprising the representation of the shield *e*, with scroll *f*, and the stars *i*, all substantially as described and shown.

5. The design for the rear plate of the lock, said design comprising the representation of the shield *e*, with scroll *f*, and the stars *i*, arranged on a striped background, *m*, all substantially as described and shown.

6. The design for the complete lock, comprising the front and rear plates, and the shackle, all substantially as described and shown.

In testimony whereof I have signed my name to this specification in the presence of two subscribing witnesses.

JOHN GÉRARD.
